[57] CLAIM

The ornamental design for a combined automobile taillight lens and grill, as shown and described.

DESCRIPTION

FIG. 1 is a perspective view of a combined automobile taillight lens and grill showing the new design;

FIG. 2 is a top plan view thereof on an enlarged scale;
FIG. 3 is a bottom plan view thereof on an enlarged
scale;

FIG. 4 is a left side view thereof on an enlarged scale;
FIG. 5 is a right side view thereof on an enlarged scale;
FIG. 6 is a front view thereof on an enlarged scale.
The taillight housing is shown in broken lines in FIGS.
1, 2, 3 and 5 for illustrative purposes only.

FIG. 1

FIG. 2

FIG. 3

FIG. 4

FIG. 5

FIG. 6
